UNITED STATES PATENT OFFICE.

JAMES HUTCHISON, OF NEWARK, NEW JERSEY, ASSIGNOR TO THOS. POTTER, SON & CO., OF PHILADELPHIA, PENNSYLVANIA.

DESIGN FOR AN OIL-CLOTH.

Specification forming part of Design No. 5,572, dated March 5, 1872.

To all whom it may concern:

Be it known that I, JAMES HUTCHISON, of the city of Newark, in the county of Essex, in the State of New Jersey, have invented and produced a new and original Design for an Oil-Cloth; and I do hereby declare the following to be a specification thereof.

The said invention is fully represented in the accompanying photographic illustration, which forms a part of this specification.

What I claim as new, and desire to secure by Letters Patent of the United States, is—
The design for an oil-cloth, substantially as shown.

JAMES HUTCHISON.
